UNITED STATES PATENT OFFICE

99,094

DESIGN FOR AN INSULATED CONTAINER OR THE LIKE

John R. Morgan, Oak Park, Ill., assignor to Sears,
Roebuck and Co., Chicago, Ill., a corporation
of New York

Application January 8, 1936, Serial No. 60,482

Term of patent 14 years

To all whom it may concern:

Be it known that I, John R. Morgan, a citizen
of the Republic of Guatemala, Central America,
residing at Oak Park, in the county of Cook and
State of Illinois, have invented a new, original,
and ornamental Design for an Insulated Con-
tainer or the like, of which the following is a
specification, reference being had to the accom-
panying drawing, forming a part thereof.

Fig. 1 is a side elevation of an insulated con-
tainer or the like showing my new design.

Fig. 2 is a view similar to Fig. 1 but showing
a container as being rotated horizontally through
an angle of ninety degrees with relation to the
position shown in Fig. 1.

Fig. 3 is a top plan view of Fig. 1.

Fig. 4 is a bottom plan view of Fig. 1.

I claim:

The ornamental design for an insulated con-
tainer or the like substantially as shown.

JOHN R. MORGAN.
